US00D877742S

(12) **United States Design Patent** (10) **Patent No.:** **US D877,742 S**
(45) **Date of Patent:** **** Mar. 10, 2020**

(54) **ELECTRONIC DEVICE ATTACHMENT
PORTION OF A MOUNT FOR AN
ELECTRONIC DEVICE**

(71) Applicant: **Kenu, Inc.**, San Francisco, CA (US)

(72) Inventors: **David E. Yao**, San Francisco, CA (US);
Leonard John Duran, Mill Valley, CA (US); **Gregory D. Caneer**, Oakland, CA (US); **Kenneth Y. Minn**, San Francisco, CA (US)

(73) Assignee: **Kenu, Inc.**, San Francisco, CA (US)

(**) Term: **15 Years**

(21) Appl. No.: **29/683,242**

(22) Filed: **Mar. 12, 2019**
